UNITED STATES PATENT OFFICE.

MOLLIE S. GARNES AND GEORGE HENRY ZIMMERMAN, OF POCAHONTAS,
VIRGINIA; SAID GARNES ASSIGNOR TO SAID ZIMMERMAN.

WASHBOARD.

SPECIFICATION forming part of Letters Patent No. 554,177, dated February 4, 1896.

Application filed April 17, 1895. Serial No. 546,068. (No model.)

To all whom it may concern.

Be it known that we, MOLLIE S. GARNES and GEORGE HENRY ZIMMERMAN, citizens of the United States, residing at Pocahontas, in the county of Tazewell and State of Virginia, have invented a new and useful Washboard, of which the following is a specification.

This invention relates to an improvement in washboards.

10 The object of the present invention is to provide a washboard with novel means whereby the same is adapted to be held in place within the washtub at any desired angle or inclination, thus obviating the liability of 15 the washboard slipping and interfering with the work.

Other objects and advantages of the invention will appear in the course of the subjoined description.

20 The invention consists in a washboard having its side frame-bars grooved on their outer opposite faces, and provided with slotted retaining-plates, within which are mounted longitudinally-sliding blocks which carry angular clamping-jaws, said clamping-jaws being adapted to engage with a washtub for the purpose of holding the washboard at the desired inclination relatively thereto.

25 The invention further consists in certain novel features and details of construction and arrangement of parts, as hereinafter fully described, illustrated in the drawings and pointed out in the claim.

In the accompanying drawings, Figure 1 is 30 a perspective view of a washboard constructed in accordance with this invention and shown applied to a washtub. Fig. 2 is a sectional view taken longitudinally through one of the side bars of the washboard-frame, in line with 35 the vertically-extending slot in the retaining-plate. Fig. 3 is a detail perspective view of one of the angular clamps, showing also the sliding block in which said clamp is swiveled.

Similar numerals of reference designate 40 corresponding parts in the several figures of the drawings.

45 Referring to the drawings, the main side bars 1 of our improved washboard are connected at their upper ends by the usual head-board 2. The washboard is also provided

with the usual soap box or holder 3 and with a plurality of parallel rods 4, which are galvanized to enable them to resist rust and form the rubbing-surface of the washboard, said rods being slightly greater in length than the distance between the inner adjacent faces 55 of the side bars 1 of the washboard-frame, and let into corresponding series of sockets in the inner faces of the side bars 1, as shown. The side bars are connected at or near their top 60 and bottom by suitable tie bolts or rods 5 and nuts, which prevent their moving apart and releasing the rods 4.

The outer opposite faces of the side bars 1 of the washboard-frame are grooved lengthwise and adapted to receive an oppositely-disposed pair of sliding blocks 6, which are held in place within said grooves by means of an elongated slotted plate or metallic strip 7, the slot in which is appreciably narrower 65 than the width of the groove and also the width of the sliding block, which moves lengthwise of said groove. The slotted retaining-plate 7 may be held in place by means of screws or other suitable fastening device, 70 and is adapted to effectually prevent the escape of the sliding blocks, while at the same time permitting them to move freely within the slots.

An oppositely-disposed pair of angular 75 clamps 8 are pivotally connected with said sliding blocks 6, as more clearly illustrated in Fig. 3, said clamps being approximately V-shaped and provided with set-screws 9 in the outer or rear arms thereof, by means of 80 which said clamps are adapted to be engaged positively with the washtub upon the outside.

By reference to Fig. 1 the manner in which the improved washboard is applied will be readily understood. The washboard is placed 90 within the tub and the angular clamps are drawn upward and passed over the upper edge of the tub sides. The washboard is now manipulated to bring it to the desired angle or inclination with relation to the tub, when 95 the set-screws of the clamps are tightened against the exterior surface of the washtub, which has the effect of holding the washtub rigidly in its inclined position until released by reversing the set-screws.

The washboard as above constructed is very simple and may be manufactured at slight cost.

It will be apparent that the form of the 5 clamps may be changed, if desired, and that other changes in the form, proportion and minor details of construction and arrangement may be resorted to without departing from the spirit or sacrificing any of the 10 advantages of this invention.

Having thus described the invention, what is claimed as new, and desired to be secured by Letters Patent, is—

15 In a washboard, the side bars or uprights provided with longitudinal grooves in their outer faces, in combination with blocks slidably mounted therein, angular clamping-

arms having laterally-deflected shanks swiveled in said sliding blocks, set-screws carried by said clamping-arms, and slotted retaining- 20 plates set into the opposite outer faces of the side bars and permitting the passage of the shanks of the clamping-arms while preventing the escape of the slide-blocks to which said clamping-arms are swiveled, substantially as specified. 25

In testimony that we claim the foregoing as our own we have hereto affixed our signatures in the presence of two witnesses.

MOLLIE S. GARNES.

GEORGE HENRY ZIMMERMAN.
